UNITED STATES PATENT OFFICE.

FRANK JARDINE AND FERDINAND JEHLE, OF CLEVELAND, OHIO, ASSIGNEES, BY
MESNE ASSIGNMENTS, TO ALUMINUM MANUFACTURES, INCORPORATED, OF
CLEVELAND, OHIO, A CORPORATION OF DELAWARE.

PISTON.

Application filed May 2, 1921. Serial No. 486,371.

To all whom it may concern:

Be it known that we, FRANK JARDINE and FERDINAND JEHLE, citizens of the United States, residing at Cleveland, in the county of Cuyahoga, State of Ohio, have invented certain new and useful Improvements in Pistons, of which the following is a specification, reference being had therein to the accompanying drawings.

10 This invention relates to pistons for internal combustion engines and has for its principal object the provision of a piston having a yieldable skirt capable of conforming to the walls of an engine cylinder at all 15 working temperatures.

Another object is to construct a piston provided with means whereby the mechanical expansion of the skirt of the piston, due to the thermal expansion of the piston head, 20 is minimized and may be accommodated in an engine cylinder.

Another object is to provide a piston having a yieldable skirt portion capable of contacting thruout its circumferential length 25 with the walls of a cylinder at various piston temperatures.

Another object is to provide an aluminum alloy piston having a yieldable skirt capable of conforming, at all working temperatures, 30 to the walls of a cylinder which is composed of material having a relatively small coefficient of expansion, as compared with aluminum alloys.

Another object is to provide a piston for 35 an internal combustion engine having a yieldable portion varying in wall thickness in the direction of its circumferential length.

Other objects will be pointed out herein-after.

40 In the following specification, our invention is described in sufficient detail to enable others skilled in the art to practice it, reference being had in the specification to the drawings which are attached to and form a part thereof, in which:

Fig. 1 is a side elevation of one form of piston, embodying our invention;

Fig. 2 is a sectional view taken on line 2—2 of Fig. 1 in the direction indicated;

50 Fig. 3 is a bottom plan view of Fig. 1; and

Figs. 4, 5 and 6 are views similar respectively to Figs. 1, 2 and 3 of a modified form of piston.

The form of piston illustrated in Figs. 1, 55 2 and 3 comprises a piston head 1, and a skirt 2 attached thereto. The skirt 2 which is substantially cylindrical has two oppositely disposed bearing walls 3, joined by two opposite walls 4, the outside diametrical 60 dimensions of all of which are substantially the same as the diameter of the engine cylinder in which the piston is to reciprocate. The walls 3 and 4 thus practically engage with the cylinder walls when the piston and 65 cylinder are assembled.

Attached to the head 1 on opposite sides thereof, are boss carrying walls 5 which are depressed inwardly or relieved on the outer surface sufficiently to provide ample clearance for all purposes between the walls and the cylinder. Walls 5 have their junction to head 1 strengthened by a cross rib 6 which also assists in supporting the bosses 7. Each wall 5 is united to both of the bearing 75 walls 3 and together constitute the only connection between walls 3 and head 1.

The walls 5 are relieved or depressed within the outer cylindrical contour of the skirt to a marked extent as is shown in Figs. 80 1 and 2, or even to a greater amount, and are separated from walls 4 by circumferential slots 8, or by openings cored out during the casting of the piston, thru which excess oil on the cylinder walls may escape into 85 the interior of the piston and be returned to the oil reservoir. A tapered or beveled upper edge 9 on each wall 4 assists in the removal of oil from the cylinder walls.

Each bearing wall 3 is separated from 90 head 1 by circumferentially extending slots 10 and one wall has a slot 11 joining slot 10 intermediate its ends and extending to the open end of the skirt, thus forming two 95 yieldable portions 12. Slot 11 may join slot 10 at various other points, even at an end thereof in which case only one yieldable portion is formed. If desired, a similar slot 11 may be formed in each bearing wall. When assembled in an engine the pistons 100 preferably have the slot 11 located on the side of the piston which takes the least lateral thrust.

When the piston becomes more highly heated in use than the cylinder, or when, for 105 other reasons, its outside diametrical dimensions tend to become greater than the inside diameters of the cylinder, the yieldable por-

tions 12 are capable of springing or bending inwardly to compensate for the increased size of the piston and to permit its moving in the cylinder without scoring.

- 5 Preferably the portions 12 increase in wall thickness in the direction of their length from their free ends to their point of support or junction with the skirt, which is indicated approximately by line 13-13 in
10 Fig. 1. When so formed, the inwardly directed force, applied by the cylinder walls on the portion, will be absorbed by the entire portion. The deflection or bending will therefore be distributed over the entire
15 length of the portion and will be substantially uniform in amount throughout the length thereof.

It will be evident that the resistance offered by the yieldable portion to any bending force can readily be increased or diminished by varying the thickness or length of the portion. Likewise the wear on the yieldable portion which varies directly with the resistance to deflection, can be regulated
25 by changes in wall thickness and length.

The modified form of piston shown in Figs. 4, 5 and 6 resembles the preferred form in many particulars. It consists of a head 21 and a substantially cylindrical skirt 22
30 of approximately the same outer diameter as the inside diameter of the cylinder and carrying the usual wrist pin bosses 23 which are supported in part from the head 21 by webs 24. These webs 24 may, if desired, be
35 united by a connecting web as shown in Fig. 2. Adjacent the ends of each boss 23, the exterior cylindrical surface of the skirt is relieved several thousandths of an inch over an area 25, substantially as indicated
40 in Fig. 4. Oil relief holes 26, leading inwardly from surfaces 25, permit escape of excess oil on the cylinder walls to the interior of the piston.

The bearing walls of the skirt are designated by 27 and 28. Wall 27 is preferably separated from head 21 by a slot 29, although it may be made integral with the head, if desired. It extends with a continuous and unbroken surface to the open end
50 of the skirt, while wall 28 is separated from the head by a similar, circumferentially extending slot 29 and extends lengthwise of the skirt to within a short distance of the end thereof where it is terminated by a circumferentially extending slot 30. A substantially vertical slot 31 joins the slots 29 and 30 intermediate their ends and forms two yieldable portions 32 capable of inward deflection or bending to compensate for expansion of the piston in excess of that of the cylinder. It is to be understood that the location of this slot 31 is not fixed but that it may join the slots 29 and 30 at various points even at their ends, thus forming only one
55 yieldable portion.

Portions 32 preferably vary in thickness in the direction of their circumferential length from a maximum at the point of support to a minimum at the free end to provide for a varying deflection of the portions
70 as has been described in connection with the modification shown in Figs. 1, 2 and 3.

Between slot 30 and the open end of the skirt the outer surface of the latter is relieved circumferentially, the relieved surface 75 33 being eccentric with respect to the cylindrical surface of bearing wall 27. The maximum relief, amounting to several thousandths of an inch depending upon the size of the piston, thus lies immediately below the center line of bearing wall 28.

As the piston expands in excess of the expansion of the cylinder, the bearing walls 27 and 28 press more tightly against the cylinder walls, yieldable portions 32 bending inwardly to compensate for this excess expansion and to maintain the diameter of the bearing walls substantially the same as that of the cylinder. The skirt of the piston thereby automatically conforms to the cylinder until it has increased to such an extent that surface 33 contacts with the cylinder walls, when the yielding action of the portions 32 is of practically no further advantage. Surface 33 is, however, relieved sufficiently to permit the calculated maximum expansion of the skirt before the surface can engage the cylinder wall.
90
95

Provision has been made against the passage of excess oil past the piston and into the combustion chamber. Little oil can pass the bearing walls of the piston due to the close fit in the cylinder. Between these bearing wall surfaces, the walls which comprise parts of the cylindrical surface of the skirt have relatively close engagement with the cylinder and thus prevent the passage of oil while the depressed surfaces adjacent the bosses and their relief openings afford means of collecting and draining oil from the cylinder walls.
100
105

In each piston herein disclosed, the longitudinal slot is shown meeting the circumferential slot or slots intermediate their ends. It is to be understood, however, that substantially the same advantages could be obtained if the longitudinal slot should join the circumferential slots at or near one end thereof, thereby forming only one yieldable portion. The wall thickness of such portion may vary, as in the above described portions.
110
115

Altho only one piston metal has been mentioned specifically in this specification, it is to be understood that the invention is applicable to all suitable piston metals or alloys having a coefficient of expansion greater than that of iron, for example, magnesium and its alloys.
120

Altho we have shown and described two modifications of our invention, we do not
125
130

wish to have it limited to the particular details set forth since these modifications are intended to be merely illustrative. Many changes, falling within the scope of our invention, will doubtless occur to those skilled in the art after a knowledge of these disclosures is obtained. We, therefore, desire that our invention be limited only to what is claimed.

10 What is claimed:—

1. A piston for an internal combustion engine comprising an integral head and skirt, cylinder engaging bearing walls in the skirt, and a yieldable portion in one of the said bearing walls varying in wall thickness in the direction of its circumferential length from a maximum at its point of support to a minimum at its free end.
2. A piston for an internal combustion engine comprising a head and a skirt integral therewith, wrist pin bosses in the skirt, the skirt having oppositely disposed bearing walls extending from adjacent the head to the end of the skirt, one of the said walls comprising a yieldable portion having a substantially cylindrical exterior surface extending to below the bosses from adjacent the head and a relatively nonyieldable portion separated from the yieldable portion by a circumferential slot and having an exterior surface of shorter radius than the surface of the said yieldable portion.
3. A piston for an internal combustion engine having an integral head and skirt, the skirt comprising a continuous, unbroken bearing wall, an oppositely disposed bearing wall provided with a circumferentially extending yieldable portion varying in wall thickness in the direction of its length and an annular wall offset inwardly with respect to the said yieldable portion.

4. A piston for an internal combustion engine comprising a head and a skirt, the skirt having a plurality of flexible circumferentially extending portions varying uniformly in wall thickness in the direction 45 of their free ends.

5. A piston for an internal combustion engine comprising a head and a skirt integral therewith, wrist pin bosses in the skirt, the skirt having oppositely disposed bearing walls extending from adjacent the head to the end of the skirt, one of the said walls comprising a yieldable portion having a substantially cylindrical exterior surface extending to below the bosses from adjacent 50 the head and a relatively nonyieldable portion separated from the yieldable portion by a circumferential slot and having an exterior surface of shorter radius than the surface of the said yieldable portion.

6. A piston for an internal combustion engine comprising a head and a skirt integral therewith, wrist pin bosses in the skirt, the skirt having oppositely disposed bearing walls extending from adjacent the head to 55 the end of the skirt and provided with substantially cylindrical exterior surfaces, one of said walls being composed of separate portions of substantially the same inside diameters and different outside diameters, 60 the portion of greater outside diameter being separated from the head and the portion of smaller outside diameter by circumferential slots, and having a longitudinal slot joining the circumferential slots intermediate 65 their ends.

In testimony whereof we affix our signatures.

FRANK JARDINE.
FERDINAND JEHLE.
